UNITED STATES PATENT OFFICE.

JOHN KASMEIER, OF FLORENCE, ALABAMA.

DELINTING-MACHINE.

SPECIFICATION forming part of Letters Patent No. 691,272, dated January 14, 1902.

Application filed June 7, 1900. Serial No. 19,437. (No model.)

To all whom it may concern:

Be it known that I, JOHN KASMEIER, a citizen of the United States, residing at Florence, in the county of Lauderdale and State of Alabama, have invented a new and useful Delinting-Machine, of which the following is a specification.

My invention relates to machines for treating cotton-seed, and particularly to that class of machines known as "delinters," adapted for the separation of the lint from the seed.

One object of my invention is to effect improvements in the means for delinting the cotton-seeds.

Another object of my invention is to combine with the delinting-brush spurred retaining-rollers which serve in coacting with the delinting-brush to rotate the cotton-seeds during the delinting process, and thereby expose all the surfaces thereof to the action of the delinting-brush.

Another object of my invention is to combine with the delinting-brush and the retaining-rollers retaining-bars to prevent the cotton-seeds from moving from the surface of the delinting-brush at the points between the retaining-rollers and to provide said bars with brushes which coact with the retaining-rollers.

With these and other objects in view my invention consists in the peculiar construction and combination of devices hereinafter fully set forth, and pointed out in the claims.

In the accompanying drawings, Figure 1 is a sectional view of the delinting-machine constructed in accordance with my invention. Fig. 2 is a side elevation of one side of my improved delinting-machine. Fig. 3 is a similar view of the reverse side thereof. Figs. 4 and 5 are detail views.

In the embodiment of my invention I provide a cylindrical revoluble brush 1, the shaft 2 of which is mounted in bearings in the sides of an inclosing case 3. A series of rollers 4, which are cylindrical in shape, are arranged concentrically around the cylindrical brush 1 and in contact therewith and are provided with projecting spurs or studs 5, which coact

with the cylindrical brush in the delinting of the cotton-seeds. The cylindrical brush 1 is rotated at a high rate of speed, and the cylindrical rollers 4 are rotated at a comparatively low rate of speed, the contacting surfaces of cylindrical brush 1 and rollers 4 moving in the same direction, as indicated by the arrows in Fig. 1. Owing to the difference in the speed of the cylindrical brush 1 and the rollers 4 the bristles or wires of the brush 1 in moving past the coacting surfaces of the rollers 4, which retard the seeds in their progress between the coacting surfaces of the brush 1 and rollers 4, delint the cotton-seeds, the lint being carried by the revoluble brush 1, and said brush also serving to polish the cotton-seeds, the functions of the rollers 4 being to hold the seeds in contact with the wires of the brush 1 while the same are being delinted and by the rotation thereof to turn the cotton-seeds during the delinting process, so as to present all surfaces of the cotton-seeds in succession to the action of the delinting-wires of the brush.

A series of retaining-bars 6 are disposed transversely and secured in the casing 3, the said bars bearing upon the surface of the revoluble brush 1 and one of said bars being disposed between each pair of the rollers 4 in the spaces between the proximate sides of said rollers and the surface of the revoluble brush 1. The function of these retaining-bars is to keep the cotton-seeds in contact with the revoluble brush 1 as the cotton-seeds are by the rotation of said brush swept from one roller 4 to another in rotation throughout the series of the rollers 4, and to enhance the efficiency of the said retaining-bars the same are provided on opposite sides with brushes 7, the length of which is coextensive with that of the said retaining-bars, the said brushes impinging against the sides of the rollers 4 which are opposed to each other, as shown, said brushes serving to prevent the cotton-seeds from being carried by the revolving rollers 4 from the coacting surface of the revoluble brush 1. It will be understood that by this construction and combination of

devices the cotton-seeds are treated by the coacting brush 1 and rollers 4 successively by each of the series of rollers 4, and as said rollers serve to impart rotatory motion to the cotton-seeds during the delinting process the machine is efficient in entirely delinting the cotton-seeds and polishing the surfaces thereof.

A feed hopper or chute 8, with which the casing 3 is provided, conducts the cotton-seed to the surface of the revoluble brush 1 on one side thereof, and below the said hopper or chute is a revoluble cleaning brush and fan 9, the same coacting with the brush 1 and serving to strip the lint from said brush

1. The said combined cleaning brush and fan during the operation of the machine rotates at a high rate of speed and creates a current of air which passes through a discharge-opening 10 in one side of the casing 3, that communicates with a pneumatic conveyer-flue, the lint by the combined action of centrifugal force generated by the revolution of the brush 9 and the current of air created thereby being detached from the brush 9 and conveyed pneumatically through the conveyer-flue to the gins or a suitable receptacle. The last of the series of rollers 4 is disposed at some distance below the cleaning and fan brush 9 and above a seed-conveying flue 11, and as the delinted cotton-seeds emerge from between the coacting surfaces of the revoluble brush 1 and the said roller 4 the seeds drop from the said roller through the said flue 11, as will be understood. A revoluble and spurred roller 12 is disposed and rotates in the feed hopper or chute 8, the function of the said roller being to agitate the seed-cotton and prevent the same from choking the said hopper or chute.

The brushes 1 9 and the rollers 4 and 12 may be rotated by any suitable means, and I do not limit myself in this particular. In Fig. 2 of the drawings the shafts of the rollers 4 are provided at one end with sprocket-wheels 13. The shaft of brush 9 is provided with sprocket-wheels 14 15. The shaft of brush 2 is provided with a sprocket-pinion 16, and an idle sprocket-wheel 17 is disposed at one side of the pinion 16. An endless sprocket-chain 18 engages the sprocket-wheels 13 14, and an endless sprocket-chain 19 connects the sprocket-wheels 15 17 and engages the sprocket-pinion 16. The shaft of the cylindrical brush 1 is provided at the end thereof opposite the pinion 16 with a pulley 20, to which power is applied by an endless belt from an engine or other suitable source of power, and the said pulley 20 is also connected to a small pulley 21 on the shaft of the cleaning and fan brush 9 by an endless belt 22, as shown in Fig. 3.

Having thus described my invention, I claim—

1. The combination of a casing having a feed-hopper, a discharge-flue for seeds and a

discharge-opening for lint, a revoluble delinting-brush and a series of retaining-rollers, disposed concentrically on said brush, from the feed-hopper to the seed-discharge flue, and a cleaning-brush, coacting with the said delinting-brush, at a point opposite the lint-discharge opening and between the feed-hopper and seed-discharge flue, said delinting-brush and retaining-rollers coacting to delint the seeds, and convey the delinted seeds to the seed-flue, and said cleaning-brush and delinting-brush coacting to strip the lint from the latter and discharge the same pneumatically through the lint-discharge opening, substantially as described.

2. In a delinting-machine, the combination of a revoluble delinting-brush, a series of revoluble retaining peripherally-spurred rollers disposed around the same, said delinting-brush and retaining-rollers coacting, and the spurs of each of said rollers operating in planes disposed in the spaces between the spurs of the opposing rollers, and means to rotate said delinting-brush at high speed and said retaining-rollers, at low speed, substantially as described.

3. In a delinting-machine, the combination of the revoluble delinting-brush, the series of retaining-rollers coacting therewith and the retaining-bars disposed between the opposing sides of said retaining-rollers, and coacting with said delinting-brush, said retaining-bars having brushes coacting with said retaining-rollers, for the purpose set forth, substantially as described.

4. In a delinting-machine, the combination with a casing having a feed and a lint-discharge opposite each other, on one side of said casing, of a revoluble delinting-brush in said casing, on one side of said feed and lint-discharge, the motion of which brush is effective in moving seed-cotton in a direction at right angles to the axis of said brush, from said feed to said discharge, the seed-cotton moving with said brush through less than a complete revolution of the latter, and means coacting with said delinting-brush to dispose and retain seed-cotton on the surface of the latter and retard the passage of the seed from the feed to the point of discharge, said brush carrying the lint while the passage of the seed in process of being delinted is retarded, and means coacting with the brush and interposed between the feed and the lint-discharge, to strip the lint from the brush and prevent the passage of lint from said feed to said discharge otherwise than between said brush and said retaining and retarding means, substantially as described.

5. In a delinting-machine, the combination with a casing having a feed and a discharge, opposite each other, of a revoluble high-speed delinting-brush, the motion of which is effective in moving seed-cotton in a direction at right angles to its axis, from said feed to

said discharge, the seed-cotton moving with
said brush through less than a complete revo-
lution of the latter, positively-driven low-
speed retaining-rolls, disposed around said
brush from the feed to the discharge, to re-
tard the passage of the seed from the feed to
the discharge, and means to strip the lint
from the brush, substantially as described.

In testimony that I claim the foregoing as
my own I have hereto affixed my signature in 10
the presence of two witnesses.

JOHN KASMEIER.
